UNITED STATES PATENT OFFICE.

JOSEPH H. THOMPSON, OF CINCINNATI, OHIO.

SAW GUIDE.

Application filed May 2, 1923. Serial No. 636,212.

To all whom it may concern:

Be it known that I, JOSEPH H. THOMPSON, a citizen of the United States of America, and a resident of Bond Hill, Cincinnati, in the county of Hamilton and State of Ohio, have invented a new and Improved Saw Guide, of which the following is a description.

My invention relates to a saw guide adapted to be used for cutting miters at any desired angle and has for an object to provide a saw guide of the indicated character improved in various particulars as will appear from the specific description following, whereby to simplify the construction, promote convenience, and in use to adapt the device for general work as for example in squaring studding joists, or siding, or cutting rafters, and the like.

Reference is to be had to the accompanying drawings forming a part of this specification, it being understood that the drawings are merely illustrative of one example of the invention.

Figure 1 is a perspective view of a saw guide embodying my invention, showing the same in use;

Figure 2 is a front elevation with the upper portion lowered;

Figure 3 is a vertical section as indicated by the line 3—3, Figure 1;

Figure 4 is a plan view;

Figure 5 is a detail in horizontal section on the line 5—5 in Figure 1.

In carrying out my invention in accordance with the illustrated example a base 10 is provided having a central depending flange or rib 11 adapted to be placed against an edge of the material A to be cut by the saw B.

On the base 10 is advantageously an arched covering 12 provided for conveniently holding the base firmly in position with one hand. At one end of the base is a vertical socket 13 in which a tubular guide standard 14 is received, said standard fitting the socket 13 and having an annular groove 15 into which a set screw 16 may be protruded. The socket 13 at the upper edge has graduations as at 17 and the standard 14 at the enlarged lower end has a mark 18 to be brought into alinement with any of the graduations 17 for angularly setting said standard to suit the particular angle of the miter.

An element 19 has vertical sliding move-

ment in the guide standard 14 and has a square or other non-circular cross section so that its movement will be limited to a vertical one and turning of the said element in said standard 14 will be prevented. The guide element 19 depends from a lateral flange 20 on the upper edge of a broad saw guide element 21 disposed vertically at a side of the standard 14 beyond the base 10. On the face of the element 21 are flat retaining fingers 22 spaced from and parallel with said face and secured as by rivets 23 or the like. A stud 24 projects from the face of the element 21 approximately central between the fingers 22.

With the above described construction, the base 11 is positioned on the material A to be cut and the set screw 16 is loosened sufficiently to permit turning of the guide standard 14 about its own axis according to the angle of the miter to be cut. The saw is now entered in the element 21 between the face of said guide and the fingers 22 until the pin 24 rests on the saw at the back edge whereby the element 21 and depending guide element 19 will be sustained on the saw and free to respond to the movements of the saw by vertical guided movement in the standard 14. Thus, the device can be held firmly with one hand on the material while the other hand enters and positions the saw in the element 21.

I would state in conclusion that while the illustrated example constitutes a practical embodiment of my invention, I do not limit myself strictly to the exact details herein illustrated, since, manifestly, the same can be considerably varied without departure from the spirit of the invention as defined in the appended claims.

Having thus described my invention, I claim:

1. A saw guide including a base, a tubular guide standard turnably adjustable on said base at one end, means to hold the standard in adjusted position, and a saw guide element presenting a broad surface, fingers parallel with the face of said guide element and spaced therefrom to accommodate the saw, a pin projecting laterally from the face of said guide element approximately central between said fingers, a lateral flange on said element at the back, and a depending element rigid with said flange and having free guided vertical movement in said tubular standard; said

depending element being constrained to partake of the turning movements of said standard but restrained against turning movement relatively to the standard.

5 2. A saw guide including a base adapted to be positioned on the material to be cut, a tubular standard supported on said base and turnably adjustable thereon, means disposed at a side of the standard and parallel with the axis thereof adapted to re-

ceive a saw, and a vertical member rigid with said saw guide means and having free guided movement vertically in said standard, said rigid member being constrained to partake of the turning movements of the tubular standard but freely movable vertically therein while restrained against turning movement in said standard. 15

JOSEPH H. THOMPSON.
